DESIGN FOR A COMBINATION MUFF AND POCKETBOOK

William Taks, Brooklyn, N. Y.

Application July 7, 1939, Serial No. 85,884

Term of patent 3½ years

To all whom it may concern:

Be it known that I, William Taks, a citizen of the United States of America and resident of the county of Kings, Borough of Brooklyn, city and State of New York, have invented a new, original, and ornamental Design for a Combination Muff and Pocketbook, of which the following is a specification, reference being had to the accompanying drawing, forming a part thereof.

In the drawing:

Figure 1 is a top plan view of a combination muff and pocketbook showing my new design with the pocketbook in closed position, and with the muff ends covered by engaging flaps.

Figure 2 is a top plan view thereof with the pocketbook in open position.

Figure 3 is a front elevational view thereof in closed position.

Figure 4 is an end elevational view thereof with the muff end in open position and with the flaps disengaged and with the handle broken away for convenience of illustration.

Figure 5 is a rear elevational view of the illustration of Figure 4.

I claim:

The ornamental design for a combination muff and pocketbook, substantially as shown.

WILLIAM TAKS.
